UNITED STATES PATENT OFFICE.

MONTGOMERY SCHUYLER, OF ST. LOUIS, MISSOURI, ASSIGNOR OF ONE-HALF TO
THOMAS W. FRY, OF ST. LOUIS, MISSOURI.

IRONING MACHINE.

Application filed June 7, 1920. Serial No. 387,233.

This invention relates to ironing machines, and more particularly to domestic ironing machines in which the work passes between a padded revolving roller and a stationary heated iron curving to the curvature of the roll.

An object of the invention is to equip an ironing machine with an improved system of gearing for controlling the operation of the machine.

Another object is to provide an improved method of disengaging the roll from the driving mechanism.

Another object of the invention is to provide an improved method of utilizing the energy latent in a part of the gearing, but which is generally lost by being absorbed by the machine frame. By utilizing this energy I have been able to provide a way whereby the iron may be drawn up to and pressed against the roll, thus making it unnecessary for the operator to use muscular force for this purpose, as is usual in the ordinary machine built for domestic ironing.

Another object of the invention is to provide an improved gearing for operating a machine of the character mentioned, including a clutch composed of a stopping member and of a clutch plate, which plate in the present case is in the form of a disc loosely mounted upon the shaft of the roll, but in rigid connection with one of the gears of a planetary gearing by which the roll is operated, in combination with novel means for controlling the clutch member or plate.

Another object of my invention is to provide a means whereby the iron will automatically separate from the roll whenever the machine is stopped, and will automatically be returned to contact when the machine is again started.

Another object of my invention is to provide a construction in which the shoe ironing member may be moved further away from the roll than is possible in many of the machines now in use, so as to afford more convenient access to the ironing surface to permit cleaning of the shoe ironing member or for other purposes as desired.

Another object of my invention is to provide a construction in which the roll ceases to revolve as soon as the shoe ironing member separates from the roll, thus permitting

the operator to insert several folded pieces between the shoe ironing member and roll 55 before again engaging them.

Other objects of the invention will appear from the following description in which reference is made to the accompanying drawings showing one form of my invention, 60 and in which—

Fig. 1 is a view showing my improved planetary gearing in connection with an ironing machine this view of the drawing showing the gearing just at the moment 65 that the stopping member has been disengaged from the clutch plate.

Fig. 2 is a rear elevation of the machine.

Fig. 3 is an end elevation of part of the gear housing, it being broken away and 70 part of the gears shown diagrammatically.

Fig. 4 is a cross sectional view on the line 4—4 of Fig. 2.

Fig. 5 is an inner end elevation showing 75 in detail the construction and arrangement of the brake device acting to stop operation of the roll when the shoe ironing member begins to separate from the roll.

Fig. 6 (Sheet 3) is a detailed view of the 80 brake device showing the manner in which said device acts to stop operation of the roll.

As shown my improved ironing machine comprises appropriate frames 1 which preferably support the entire ironing mechanism 85 and the operating motor therefor. The motor 2 is supported by the framing of the machine below the ironing mechanism and out of the way so that it will not interfere with the operator in charge of the machine. 90

The shaft 3 which supports the padded roll 4 is journaled for rotation in the upper members 5 of the machine frame, and supports the gearing for operating the roll from the motor. The belt 6, driven by the 95 motor, passes over an appropriately constructed pulley 7 journaled for rotation upon and relative to the shaft 3. The pulley 7 supports a pair of stud shafts 8, to each of which a pair of gears is secured. The gears 100 9 which are rigid on the inner ends of the stud shafts 8 engage diametrically opposite portions of a gear 10 which is loose on the shaft 3 and which is in rigid connection with a clutch member or plate 11 also loosely supported upon the shaft 3. The gears 12,

which are rigid on the outer ends of the stud shafts, mesh with diametrically opposite portions of a gear 13 which is keyed to the shaft 3. As shown, the gears 9 and 10 are of uniform diameter and are provided with an equal number of teeth; whereas, the gear 13 is of less diameter than the gear 10 and also of less diameter than the gears 12, and is provided with a smaller number of teeth than the gears 12. For instance, the gears 12 may be formed with thirty-eight teeth and the gear 13 may be formed with thirty-seven teeth, although, of course, the proportions may be varied and the same result of operation obtained.

In the embodiment shown, the planetary members of the gearing which are supported by the pulley 7 are carried around the central members of the gearing in a counter-clockwise direction when viewed as in Fig. 3. If, as in the present case, the clutch member or plate 11 is not held stationary with respect to the machine frame 5, the gear 10 and the clutch member 11 tend to revolve together around the shaft 3, while the gear 13 and the shaft remain stationary. In such case also, the gears 12 turn upon their axes in a counter-clockwise direction, it being understood that when the clutch member 11 and the gear 10 are held from rotation, the gears 9 and the gears 12 are forced to turn upon their axes in a counter-clockwise direction, thus operating the roll in a clockwise direction when viewed as in Fig. 3, or in a counter-clockwise direction when viewed as in Fig. 4.

The cooperating or stopping member, which is used in connection with the clutch plate 11 to prevent it from rotating, comprises a connecting arm or lever 14, which, in the embodiment shown, is pivoted to the upper portion of one member of a cradle comprising a pair of members 15. As shown, the lower ends of the cradle members are attached to a shaft 16 supported horizontally below and parallel with the axis of the roll 4, though the pivotal support may be located elsewhere if desired. Said cradle supports the ironing member 17 or shoe 17 which curves properly relative to the curvature of the roll 4 in order to iron the clothing or material passing between the roll and said ironing member or shoe. The connecting arm or lever 14 is provided with a projection 18 whereby connection may be made, through a slot 19 in the inner wall of the gear housing, with the clutch member or plate 11. In the embodiment shown, this connection is made by extending the projection 18 into any one of a concentric series of holes 20 in the clutch member or plate 11. In this arrangement, when the projection 18 is inserted in any one of the holes 20, the revolution of the clutch plate 11 will exert a tractive effort

through the arm or lever 14, drawing the cradle 15 together with the ironing member 17 toward, and into contact with the padded roll 4. This movement of the ironing member 17 will continue until it is stopped by contact with the padded roll 4; or until the projection 18 has abutted the end of the slot 19, at which moment the clutch member or plate 11 is prevented from rotating further.

Referring to Fig. 4 it will be seen that if the connecting arm or lever 14 is pivoted on the upper member 5 of the machine frame, the engagement of the projection 18 with one of the concentric holes 20 would prevent rotation of the clutch plate 11, diverting the energy of the motor to driving the roll 4.

However, in the construction shown, when the projection 18 on the connecting arm or lever 14 is disengaged from the clutch plate 11, the weight of the cradle 15 and the iron 17 is sufficient to move the cradle and the iron away from the padded roll. The ironing member 17 is supported for rocking movements by journal members 21 mounted in bearing blocks 22 which are movably supported in guides 23 in the end members of the cradles. The bearing blocks 22 are pressed toward the roll 4 by springs 24. This arrangement is a familiar one and automatically permits proper adjustment of the ironing member 17 to conform to the requirements of the material passing through the machine.

As an incident to the movement of the cradle 15 away from the padded roll 4, a braking pressure is applied to the roll so as to stop rotation thereof. For this purpose a brake member is provided in connection with or under control of the cradle. As shown, each brake member comprises a rod 25 supported in each cradle member 15 and provided with lateral projections 26 (Figs. 5 and 6) extending within an annular flange 27 on the adjacent end of the roll 4. A spring 28 (Fig. 4) encircles the outer end portion of each rod 25 having its inner end abutting the cradle member 15 and its outer end confined within and bearing against an abutment 29 on the rod. The member 29 on each rod may be utilized to turn the brake rod to such a position that the projections 26 will pass the flange 27, and thereby permit the cradle and iron to be moved away from the roll for cleaning or other purposes desired. When the ironing member is in position for use and the machine is in operation, the projections 26 are held out of contact with the roll flanges 27 by engagement of parts 30 on the brake rods with the parts 31 on the cradle. As it is only necessary to turn the brake rod about ninety degrees to disengage the projection 26 from the flange 27, a stop abutment 32

may be provided on the cradle member to stop rotation of the brake rod when it has reached the desired position.

The movement of the cradle is thus used 5 automatically to brake and stop rotation of the roll 4, leaving the planetary gearing free to turn as previously described. This permits material to be placed on the stationary roll preparatory for a subsequent 10 operation.

It will be seen, further, that if the projection 18 on the connecting arm or lever 14 be engaged with the clutch plate 11, thus 15 pressing the ironing member 17 against the roll 4, the stopping of the motor will allow a counter-clockwise rotation of the clutch plate 11 when viewed as in Fig. 4, and a consequent separation of the ironing member and roll. When the motor is again 20 started, the clutch plate 11 will begin to revolve in a clockwise direction and will draw the ironing member 17 up against the roll 4. This permits a construction of the machine wherein all operations are carried out 25 through, or as an incident to the starting and stopping of the motor, and wherein it is impossible for the hot ironing member to remain in contact with the stationary padded roll after the roll is stopped.

30 The material may be fed into the machine from the front side thereof by passing the material over the table 33.

From the foregoing it is apparent that my invention completely and satisfactorily 35 performs its functions. The mechanism is of simple and strong construction, and operates in a highly efficient manner without the requirement of special skill or training on the part of the operator. The mechanism 40 is easily placed in operation, and the roll is automatically stopped by a force from the cradle incident to the separation of the ironing member from the roll. Furthermore, it is possible to operate the machine 45 without muscular fatigue, due to the fact that the force required to press the ironing member against the padded roll is obtained from the motor which drives the roll.

50 I do not restrict myself to unessential features, but what I claim and desire to secure by Letters Patent, is:—

1. An ironing machine of the character described comprising a roll element, a shoe 55 element, driving means to operate the roll, engageable elements in connection with said shoe and with said driving means respectively, and gears driven by said driving means having operative connection with one 60 of said engageable elements for moving one of said shoe or roll elements into cooperative relation with the other by said engageable elements when said engageable elements are in engagement and for rotating 65 said roll.

2. An ironing machine of the character described, comprising a revoluble roll, a motor, mechanism driven by the motor for operating said roll, an ironing member movable to and from position to cooperate 70 with said roll to iron fabrics passing between the roll and the ironing member, releasable connections between said ironing member and said mechanism for causing said mechanism to operate said roll and to 75 move said ironing member into cooperative relation with the roll, and means under control of said ironing member for stopping operation of said roll as an incident to movement of said ironing member from the 80 position in which it cooperates with said roll and while the motor continues to operate.

3. An ironing machine of the character described, comprising a roll, a system of planetary gearing for operating said roll, clutch mechanism controlling the operation of the roll by said gearing, an ironing member movable to and from position to cooperate 85 with said roll to iron fabrics passing between the roll and the ironing member, and means for connecting the ironing member with the clutch mechanism to draw the ironing member toward the roll and to cause said gearing to operate said roll. 95

4. An ironing machine of the character described, comprising a roll, a system of planetary gearing for operating said roll, clutch mechanism controlling the operation of the roll by said gearing, an ironing member movable to and from position to cooperate 100 with said roll to iron fabrics passing between the roll and the ironing member, means connecting the ironing member with the clutch mechanism to draw the ironing member toward the roll and to cause said gearing to operate said roll, and a device operated as an incident to movement of the ironing member from the position in which it cooperates with the roll to stop rotation 105 of the roll. 110

5. An ironing machine of the character described, comprising a roll, a rotary shaft supporting the roll, a system of planetary gearing for operating said shaft, a device 115 for controlling the operation of said shaft by said gearing, and an ironing member under control of said device for cooperating with said roll.

6. An ironing machine of the character described, comprising a rotary shaft, a roll mounted on said shaft, an ironing member movable to and from position to cooperate with said roll, a system of planetary gearing supported by said shaft for driving the 120 shaft to operate the roll, and means for utilizing energy latent in a part of the gearing 125 to press the ironing member against the roll.

7. An ironing machine of the character described, comprising a rotary shaft, a roll 130

- mounted on said shaft, an ironing member movable to and from position to cooperate with said roll, a system of planetary gearing supported by said shaft for driving the shaft 5 to operate the roll, an element in connection with said gearing, and a connection from the ironing member to said element for utilizing the energy of a part of the gearing to press the ironing member against the roll.
- 10 8. An ironing member of the character described, comprising a rotary shaft, a roll mounted on said shaft, an ironing member movable to and from position to cooperate with said roll, a system of planetary gearing 15 supported by said shaft for driving the shaft to operate the roll, means for utilizing energy latent in a part of the gearing to press the ironing member against the roll, and means controlled by the ironing member 20 to stop rotation of the roll as an incident to movement of the ironing member away from the position in which it cooperates with the roll.
9. An ironing machine of the character 25 described, comprising a rotary shaft, a roll mounted on said shaft, an ironing member movable to and from position to cooperate with said roll, a system of planetary gearing supported by said shaft for driving the 30 shaft to operate the roll, an element in connection with said gearing, a connection from the ironing member to said element for utilizing the energy of a part of the gearing to press the ironing member against the roll, and means controlled by the ironing member 35 to stop rotation of the roll as an incident to movement of the ironing member away from the position in which it cooperates with the roll.
- 40 10. An ironing machine of the character described, comprising a roll; a system of planetary gearing for operating the roll; a stopping member and a clutch plate forming a clutch for controlling the operation of the 45 roll by the gearing; and an ironing device controlled by said stopping member and held in operative position relative to the roll during the time that the stopping member and the clutch plate are in engagement.
- 50 11. An ironing machine of the character described, comprising a roll, mechanism for operating said roll, an ironing member movable to and from position to cooperate with the roll, means operable by said operating 55 mechanism for automatically moving the ironing member to position to cooperate with the roll when said mechanism is operating, and braking devices operated by the ironing member for stopping operation of the roll 60 as an incident to movement of the ironing member from position in which it cooperates with the roll.
12. An ironing machine of the character 65 described, comprising a roll, operating mechanism for said roll, an ironing member mov- able to and from position to cooperate with the roll, automatic means for moving the ironing member away from the roll, a pair of engageable elements in connection with said operating mechanism and said ironing member respectively for controlling operation of said roll by said operating mechanism, and means operated by said operating mechanism for actuating said engageable elements to move the ironing member to co- 70 operative relationship with the roll automatically when the roll is started in operation.
13. An ironing machine of the character described, comprising a roll, an ironing member arranged to cooperate with the roll and being movable from position in which it will cooperate with the roll to one position away from the roll in which it will not cooperate with the roll, devices movable by 75 the ironing member for stopping operation of the roll as an incident to movement of the ironing member to the aforesaid position in which it will not cooperate with the roll, and means for adjusting said devices to permit further movement of the ironing member away from the roll a sufficient distance to afford access to the ironing surface to permit 80 cleaning of the iron.
14. An ironing machine of the character 85 described, comprising a roll; an ironing member arranged to cooperate with the roll, a support for the ironing member arranged to support said member in position to cooperate with the roll, and to permit movement of said member away from the roll, devices for stopping movement of said ironing member away from the roll and for stopping operation of the roll as an incident 90 to movement of the ironing member away from the roll, and means for adjusting said devices to permit movement of said member away from the roll an additional distance sufficient to permit access to the ironing surface of the roll for any desired purpose.
15. An ironing machine of the character 95 described, comprising a roll, a motor for operating the roll, an ironing member arranged to cooperate with the roll, a support for the ironing member arranged to support 100 said member in position to cooperate with the roll and to permit movement of said member away from the roll, devices under control of the ironing member for stopping operation of the roll as an incident to movement of the ironing member away from the roll and while the motor continues to operate, and means for adjusting said devices in 110 position to permit further movement of the ironing member away from the roll a sufficient distance to permit access to the ironing surface of the roll for any desired purpose.
16. In an ironing machine, the combination with a shoe and a roller mounted for relative movement, one toward and away 115 120 125 130

from the other, of a motor for driving said roller, mechanism adapted to be driven by said motor for causing said relative movement between said shoe and roller and for automatically stopping such movement at different predetermined points holding the parts in that position, and means for disconnecting said mechanism so as to permit the separation of the parts independently thereof.

17. In an ironing machine, the combination of a frame, a roll shaft journaled in said frame, a differential planetary gear train mounted on said shaft and including an abutment gear loose on said shaft, means for holding said abutment gear against turning whereby to cause said gear train to drive said shaft, manually operated means for releasing said abutment gear to permit said gear train to operate idly, a motor, and driving connections from said motor to said gear train.

18. An ironing machine of the character described comprising a roll, a shaft on which said roll is supported and fastened, gearing mechanism for rotating said shaft and thereby said roll, an ironing member, an element for moving said ironing member to cooperative relationship with said roll, and a part mounted on said shaft and engageable by said element for actuating said element to move said ironing member to co-

operative relationship with said roll and for controlling operation of said shaft and said roll by said gearing mechanism.

35

19. An ironing machine of the character described comprising a roll, a shaft on which said roll is supported and fastened, gearing supported by said shaft, a motor for operating said gearing, an ironing member, engageable elements connected with said ironing member and said shaft respectively, and a gear on said shaft attached to one of said elements and engaging said gearing when controlling operation of said roll by said gearing when said elements are in engagement.

40

20. An ironing machine of the character described comprising a roll, a shaft on which said roll is supported and fastened, gearing supported by said shaft, a motor for operating said gearing, an ironing member, engageable elements connected with said ironing member and said shaft respectively, and a gear on said shaft attached to one of said elements and engaging said gearing controlling operating of said roll by said gearing when said elements are in engagement and permitting idle operation of said gearing when said elements are out of engagement and moving said ironing member to cooperative relationship with said roll when said elements are in engagement.
